UNITED STATES PATENT OFFICE.

R. W. BELSON, OF PHILADELPHIA, PENNSYLVANIA.

SKATE.

Specification of Letters Patent No. 17,414, dated June 2, 1857.

To all whom it may concern:

Be it known that I, R. W. BELSON, of Philadelphia, in the county of Philadelphia and State of Pennsylvania, have invented a 5 new and useful Improvement in the Construction of Skates; and I do hereby declare that the following is a full, clear, and exact description of the same, reference being had to the annexed drawings, making a part of 10 this specification, in which—

Figure 1, is a longitudinal vertical section of my improvement; (a), (a), Fig. 2, showing the plane of section. Fig. 2 is a plan or top view of ditto. Fig. 3 is a back view 15 of ditto.

Similar letters of reference indicate corresponding parts in the several figures.

My invention consists in constructing the skate entirely of cast metal, the skate being 20 cast in two separate and distinct parts which are longitudinal, halves, each part being composed of one half of the stock and one half of the runner. The lower and inner edges of the two parts of the runner are 25 beveled, and the two parts are secured together by means of screws as will be presently shown, the beveled lower edges of the runner when the two parts are secured together forming the usual gutter.

30 To enable those skilled in the art to fully understand and construct my invention I will proceed to describe it.

A A represent the two parts of the skate, each part being a vertical longitudinal half 35 of the stock and runner. Both parts are shown in Figs. 2 and 3. These parts are cast separately and the lower inner edges of the two parts of the runner are beveled as shown at (a) Fig. 3. The portion of the 40 skate usually termed the stock is designated by (b) and the runner portion by (c). Iron would of course be the metal employed and the two parts of the stock may be cast of any proper pattern so as to conform to the 45 foot and by means of the usual straps capable of being firmly adjusted to it.

The two parts A, A, are secured together by means of rivets or screws (d), and the beveled edges (a) of the two parts of the 50 runner (c), when said parts are secured together, form the usual gutter see Fig. 3.

By this mode of construction a cheap and durable skate is produced, and as good in every respect as the best manufactured in

the usual way. The lower edges of the two 55 parts of the runner may if desired be cast with chill so that the edges formed by the bevel or basils (a) will be sufficiently hard to prevent much wear. The runners of ordinary skates soon become dull by wear and 60 require filing to prevent them from slipping. This however is rarely done and the skates as a general thing are laid aside as useless when worn smooth.

I am aware that the runners of skates 65 have been formed of two parts and a patent was granted to J. E. Forbes for thus constructing the runners for the purpose of enabling them to be kept sharp. This mode of construction however adds to the expense 70 of the skate for the two parts of the runner are connected by a dovetail and a lap, and the runner is secured to a wooden stock. The facility of sharpening the runner will not compensate for the increased cost of 75 construction.

I am also aware that the stock formed of a certain number of parts, and the runner of a skate have been cast solid or in one piece, and that a patent was granted to B. 80 F. Shelabarger, for such mode of construction. In Shelabarger's skate, the object appears to be economy only, no reference being had to the formation of the gutter.

By having the runners, the lower part, 85 cast with a chill as in my improvement they are rendered so hard as to resist wear, or to wear so very slowly that they will not become smooth in a long time and as the cost of the skate is reduced extremely low I consider it an improvement and a preferable 90 article to any now manufactured.

I do not claim separately forming the runner of two parts for this has been previously done, neither do I claim casting the 95 stock and runner in one piece, for this has also been previously done, but

Having thus described my invention what I claim as new and desire to secure by Letters Patent is—

Constructing the skate entirely of cast metal and of two parts connected together substantially as shown and described.

R. W. BELSON.
